CLAIM

We claim the ornamental design for a plant training stake, as shown and described.

DESCRIPTION

FIG. 1 is a top perspective view of a plant training stake according to the invention.

FIG. 2 is a front elevational view of the plant training stake depicted in FIG. 1.

FIG. 3 is a left side elevational view of the plant training stake depicted in FIG. 1.

FIG. 4 is a rear elevational view of the plant training stake depicted in FIG. 1.

FIG. 5 is a right side elevational view of the plant training stake depicted in FIG. 1.

FIG. 6 is a top plan view of the plant training stake depicted in FIG. 1.

FIG. 7 is a bottom plan view of the plant training stake depicted in FIG. 1; and,

FIG. 8 is a cross sectional view taken at line 8-8 of FIG. 1. The broken lines represent portions of the article and form no part of the claimed design.
